UNITED STATES PATENT OFFICE.

MILO A. HAMILTON, OF SCOTTS, MICHIGAN.

CHUCK.

1,104,113.

Specification of Letters Patent. Patented July 21, 1914.

Application filed April 7, 1913. Serial No. 759,416.

To all whom it may concern:

Be it known that I, MILO A. HAMILTON, a citizen of the United States, residing at Scotts, Michigan, have invented certain new and useful improvements in Chucks, of which the following is a specification.

This invention relates to improvements in chucks.

The main objects of this invention are:

- 10 First, to provide an improved chuck which is adapted for holding drills having shanks of different forms or drills having driving tangs and those without driving tangs.
- 15 Second, to provide an improved chuck which is very simple and easy to adjust.
- 20 Third, to provide an improved chuck which is simple and economical in structure, and at the same time, is capable of withstanding very severe strains.
- 25 Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing forming a part of this specification, in which:

Figure I is a side view of a structure embodying the features of my invention, the shank 15 being broken away, a drill being shown in position in the chuck. Fig. II is a detail vertical section on a line corresponding to line 2—2 of Fig. III. Fig. III is a detail vertical section on a line corresponding to line 3—3 of Fig. I. Fig. IV is a detail section on a line corresponding to line 4—4 of Fig. II, showing structural details of the cross head 8. Fig. V is a detail section on a line corresponding to line 5—5 of Fig. II. Fig. VI is a perspective view 45 of one of the jaws 4.

In the drawing similar reference characters refer to similar parts throughout the several views, and the sectional views are taken looking in the direction of the little 50 arrows at the ends of the section lines.

Referring to the drawing, the frame-like body 1 is provided with opposed converging jaw seats 2. These jaw seats are longitudinally slotted at 3. The jaws 4 are plate-like in form and are provided with inclined bearing surfaces 5 coating with the

jaw seats 2. Headed pins 6, carried by the jaws 4, are arranged through the slots 3 in the jaw seats of the body. These pins are preferably threaded into the jaws for convenience in assembling the parts, and also for adjustment. The slots 3 are rabbeted at 7 to receive the heads of the screws, as shown. The cross head or member 8 is arranged to reciprocate in the body above the jaws. This cross head is preferably formed of sections 9 secured together by the bolts 10. The sections 9 of the cross head have opposed grooves 11 which, when the sections are secured face to face as shown, provide longitudinal slots 12 for the headed pins or studs 13 on the upper ends of the jaws. The sides of the body or frame 1 are provided with flanges 14 which support the jaws and the cross heads slidably within the body. As the cross head is reciprocated, the jaws are raised and lowered, and this movement, owing to the arrangement of the jaws on the seats as described, causes the jaws to move toward and from each other. The shank 15 is threaded through the top of the body or frame member and rotatably secured to the cross head by means of the head 16. See Fig. II. When the shank is turned, it is obvious that it reciprocates the cross head, and this moves the jaws in or out. The shank 15 is adapted to be inserted into the chuck of a drill press or other driving member.

The faces of the jaws are provided with alternately disposed gripping members 17 at their lower ends and with longitudinally opposed grooves 18 at their upper ends. The gripping members 17 are notched or grooved at 19 in alignment with the groove 18. Between the gripping members and the groove 18, the jaws are cut away at 20 to accommodate certain forms of driving tangs.

My improved chuck is adapted for holding various forms of drills such as drills having round, semi-round, flat, or square shanks, and shanks with or without driving tangs. My improved chuck is especially designed by me for heavy work and is well adapted for that purpose. My improvements are, however, well adapted for embodiment in light chucks or chucks designed for light work.

I have not attempted to illustrate or describe various modifications which I contemplate as I believe the disclosure made 110 will enable those skilled in the art to which my invention relates to embody the same as

taste or conditions may dictate. I desire, however, to be understood as claiming my improvements specifically in the form illustrated, as well as broadly within the scope 5 of the appended claims.

Having thus described my invention, what I claim as new and desire to secure by Letters Patent is:

1. In a chuck, the combination of the body 10 having opposed converging longitudinally slotted jaw seats, jaws having inclined bearing surfaces on their outer edges coacting with said seats, headed pins on said jaws engaging the slots of said jaw seats, a cross 15 head having longitudinal slots therein, the sides of the body being provided with inwardly projecting flanges slidably supporting said jaws and cross head, headed pins on said jaws engaging said slots in said cross 20 head, whereby, as the cross head is reciprocated, the jaws are moved to and from each other, and a driving shank having threaded engagement with the body and rotatably connected to said cross head.
2. In a chuck, the combination of the body having opposed converging longitudinally slotted jaw seats, jaws arranged in said seats, headed pins on said jaws engaging the 25 slots of said jaw seats, a cross head having longitudinal slots therein, said body being provided with side parts engaging the sides of the jaws and cross head for laterally supporting the same for sliding movement in said body, headed pins on said jaws engaging said slots in said cross head whereby, as the cross head is reciprocated, the jaws are moved to and from each other, and a driving shank having threaded engagement with the 30
3. In a chuck, the combination of the body having opposed converging longitudinally slotted jaw seats, jaws arranged in said seats, headed pins on said jaws engaging the slots of said jaw seats, a cross head having longitudinal slots therein, the sides of the body being provided with inwardly projecting flanges slidably supporting said jaws and cross head, headed pins on said jaws engaging said slots in said cross head, whereby, as the cross head is reciprocated, the jaws are moved to and from each other, and a driving shank having threaded engagement with the body and rotatably connected to said cross head.

body and rotatably connected to said cross head.

3. In a chuck, the combination of the body having opposed converging longitudinally slotted jaw seats, jaws arranged in said seats, a cross head having longitudinal slots therein, said body being provided with side parts 45 engaging the sides of the jaws and cross head for laterally supporting the same for sliding movement in said body, headed pins on said jaws engaging said slots in said cross head whereby, as the cross head is reciprocated, the jaws are moved to and from each other, and a driving shank having threaded engagement with the body and rotatably connected to said cross head.

4. In a chuck, the combination of a body 50 having opposed converging jaw seats, jaws arranged in said seats and provided with headed members on their ends, a driving shank having threaded engagement with said body and having a head on its inner end, and a cross head consisting of sections having opposed grooves coacting to provide longitudinal slots in which said headed members of said jaws and shank are engaged, the sides of the body being provided with side parts embracing the ends of said cross head whereby the same is supported for sliding movement.

In witness whereof, I have hereunto set my hand and seal in the presence of two witnesses.

MILO A. HAMILTON. [L. s.]
